US00D851108S

(12) **United States Design Patent** (10) Patent No.: **US D851,108 S**
Yuguchi et al. (45) Date of Patent: **** Jun. 11, 2019**

(54) **DISPLAY SCREEN WITH GRAPHICAL USER INTERFACE**

(71) Applicant: **MITSUBISHI ELECTRIC CORPORATION**, Tokyo (JP)

(72) Inventors: **Takashi Yuguchi**, Tokyo (JP); **Kazuhiro Hayashi**, Tokyo (JP)

(73) Assignee: **Mitsubishi Electric Corporation**, Tokyo (JP)

(**) Term: **15 Years**

(21) Appl. No.: **29/601,728**

(22) Filed: **Apr. 25, 2017**

(30) **Foreign Application Priority Data**

Nov. 9, 2016 (JP) 2016-024406

(51) **LOC (11) Cl.** **14-04**

(52) **U.S. Cl.**

USPC **D14/486**

(58) **Field of Classification Search**

USPC D14/485-495

CPC G06F 3/048; G06F 3/0481; G06F 3/04812; G06F 3/04815; G06F 3/04817; G06F 3/0482; G06F 3/0483; G06F 3/0484; G06F 17/246

(57) **CLAIM**

The ornamental design for a display screen with graphical user interface, as shown and described.

DESCRIPTION

The FIGURE is a front view of display screen with graphical user interface showing our new design.

The broken lines shown represent portions of the graphical user interface and form no part of the claimed design. The outer peripheral broken lines represent a display screen or portion thereof and form no part of the claimed design.

1 Claim, 1 Drawing Sheet
